[57] CLAIM

The ornamental design for an electrical connector
cover, as shown.

DESCRIPTION

FIG. 1 is a perspective view of an electrical connector
cover showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a side elevational view thereof of the side
opposite that shown in FIG. 1.

FIG. 1

FIG. 2

FIG. 3

FIG. 4

FIG. 5

FIG. 6
